UNITED STATES PATENT OFFICE

154,140

DESIGN FOR A KNITTING BAG OR SIMILAR ARTICLE

Paul R. Peak, Jr., Hamden, Conn.

Application February 12, 1947, Serial No. 136,866

Term of patent 3½ years

(Cl. D3—19)

To all whom it may concern:

Be it known that I, Paul R. Peak, Jr., a citizen of the United States of America, residing at Hamden, county of New Haven, and State of Connecticut, have invented a new, original, and ornamental Design for Knitting Bag or Similar Article, of which the following is a specification, reference being had to the accompanying drawing, forming a part thereof.

Fig. 1 is an elevation of a knitting bag, showing my new design;

Fig. 2 is another elevational view thereof as viewed from a diametrically opposite position and showing the cover in open position; and

Figs. 3 and 4 are bottom and top plan views respectively thereof.

I claim:

The ornamental design for a knitting bag or similar article, substantially as shown.

PAUL R. PEAK, JR.
